UNITED STATES PATENT OFFICE.

OSCEOLA C. THOMPSON, OF WHITE PLAINS, NEW YORK, ASSIGNOR TO WIREBOUNDS PATENTS COMPANY, A CORPORATION OF MAINE.

END-STAPLING MACHINE.

Application filed September 4, 1919. Serial No. 321,647.

To all whom it may concern:

Be it known that OSCEOLA C. THOMPSON, a citizen of the United States, and a resident of White Plains, in the county of Westchester and State of New York, has invented an Improvement in End-Stapling Machines, of which the following is a specification.

This invention relates to machines for stapling box heads, box ends or the like, and is intended to provide certain improvements contributing to efficiency of operation and practicability of construction of such machines.

Another object is to provide such a machine with means for forming and driving an improved staple in such a manner as to increase its holding power in the work.

The invention will be clearly understood from the following description with reference to one form of machine containing an embodiment of the invention which is shown for illustration in the accompanying drawings.

In said drawings:

25 Fig. 1 is a side elevation of the illustrative machine, parts thereof being broken away and other parts being shown in section to better illustrate the mechanism; said figure also shows a box, partly broken away, in position to be operated upon.

Fig. 2 is a rear elevation of the illustrative machine.

Fig. 3 is a top plan view of the stapling arm and mechanism carried thereby.

35 Fig. 4 is a side elevation of said arm showing said mechanism in dotted lines.

Fig. 5 is an enlarged view of a section taken on line 5-5 of Fig. 3, showing the staple forming and driving mechanism in elevation.

40 Fig. 6 is a section taken on the line A-A of Fig. 5.

Fig. 7 is an enlarged plan view of the end of the stapling arm.

45 Fig. 8 is a section taken on line B-B of Fig. 7.

Fig. 9 is a section taken on line C-C of Fig. 8.

50 Fig. 10 is a detailed plan view of the staple carrier.

Figs. 11 and 12 are top and side views respectively of the loop bar which in the illustrative machine cooperates with a staple former to form the staple.

Fig. 13 is a side of a part of the machine 55 showing in dotted lines the actuating mechanism for the staple carrier.

Fig. 14 is a rear elevation of Fig. 13.

Fig. 15 is a top plan view of the machine showing the clincher mechanism carried by 60 the upper arm and the actuating means therefor.

Fig. 16 is a side view showing the clincher mechanism in dotted lines.

Fig. 17 is a rear view of the actuating 65 means for the clincher mechanism.

Fig. 18 is a diagrammatic plan showing a box in different positions in the machine indicating the operation of stapling the box head along sides of the box. For clearness 70 of illustration, the lid or cover of the box is not shown in this figure or in Figure 19.

Fig. 19 is a plan view of the inside end of a box showing the end section stapled to the cleats of side sections and showing in 75 dotted lines the legs of the staples as deflected by the cleat material.

Fig. 20 is an enlarged view of an improved staple formed by the machine.

The illustrative machine comprises, generally, a staple forming and driving mechanism for forming staples and driving them into the work; and an automatically adjustable clinching mechanism to hold the box parts in position during the staple driving 85 operation and to clinch the ends of staples which may be driven through the work.

The staple forming and driving mechanism is carried by the arm 2 supported by 90 the frame 1.

A staple driver 5 operates at the end of the arm 2 to drive the staples from the nose of the arm, which is so formed as to permit the driving of the staples close to the box sides and in the corners and to gauge the 95 stapling point from the box sides.

The staple is formed in a holder or former 6 in the forward end of a movable carrier 7 and is driven from said holder by the staple driver 5 which is adapted to enter 100 the holder when it is in alignment therewith.

To supply the staple to said holder 6, the carrier 7 is adapted to draw back the staple holder to a cooperating staple forming instrumentality exemplified by loop bar 8 having a projection 9 cooperating with the holder to form the staple therein, said holder

being the former or die of the staple forming mechanism.

After the staple forming operation, the carrier moves forward and positions the staple to be ejected by the driver and driven into the box head.

Thus, the illustrative machine comprises a staple forming and driving mechanism in which the staple is driven from the part in which it is formed.

An advantage, among others, in forming the staple in the part from which it is driven is that the staple may be formed and driven with longer legs than would be the case if the staple had to be transferred from the former to a carrier.

In stapling box heads, the preferable practice is to drive the staples upwardly from within the box in order that the operator may more readily manipulate the box and observe the operation. The illustrative machine is designed accordingly; the stapling arm 2 affording a support for the box head and the staple driver being arranged to drive the staple upward from the nose of said arm into the box ends and close to the sides.

The staple is formed in the holder 6 of the carrier 7 by the downward stroke of the loop bar 8 forcing the staple wire into the holder 6 and thereby bending the wire downward into the desired U-shape and when the carrier advances the staple to the end of the stapling arm, the driver enters the bottom of the holder and forces the staple up into the work. Thus, the staple is formed pointing up and is transferred from forming to driving position without inverting, turning, tilting or deflecting the staple.

To provide room for action of the loop bar and associated wire feeding and cutting devices above the staple holder but below the top of the stapling arm, the carrier 7 is arranged to slide in an inclined guide 10 which brings the staple holder 6 below the projection line of the loop bar for the forming operation, and carries it flush with the upper surface of the stapling arm at the driving position. Thus, the staple is simply shifted forwardly and upwardly without any tilting or turning with its legs always pointing the same way.

The staple wire 4 drawn from a supply reel 11 in the machine standard is fed by co-acting feed and gripping rolls 12 and 13 and is guided by a tube 14 which projects the staple wire in position for cutting and to be drawn by the loop bar into the staple former or holder 6.

The inner end of the guide tube which is carried in a spring held lever 15 is formed as a cutter 16 to co-act with a stationary knife 17 to sever the portion of wire required for a staple.

Movement of the guide tube to sever the

wire takes place at the beginning of the downward stroke of the loop bar, and this is effected by means of a latch 18 on the loop bar engaging the end of the lever 15 said latch being released from said lever as soon as the wire is severed by co-action of cam lugs 19 and 19^a, one on the latch and one fixed, whereupon the lever and guide tube are returned to normal position by means of a spring 20.

Thus the guide tube through which the staple wire passes constitutes a movable cutter and the staple wire and guide tube both move during a wire severing operation. This enables the use of a staple holder or former which remains stationary during a staple forming operation, the projection 9 of the loop bar 8 moving into and out of the former to form the staple.

An advantage, among others, in this arrangement is that the staple which is formed in the holder or former 6 may be quickly and easily shifted to the driving point and may be driven from the holder in which it is formed thus obviating the transfer of the staple from the former to a carrier.

Referring to Figs. 3, 4 and 5 it will be noted that in the illustrative machine the staple wire passes in a horizontal plane between the cutters which operate in a vertical plane at an angle of about 30 degrees to the longitudinal axis of the staple wire. Thus when the staple is formed the points of the legs will be oppositely disposed as shown in Fig. 20 which will cause the legs to run in opposite directions when driven into the work as shown in Fig. 19.

Referring to Figs. 3 and 7-11, it will also be noted that the staple former and loop bar are constructed and arranged to form the staple with its points vertical but in a plane at an angle of about 45 degrees to the medial longitudinal axis of the stapling arm, the holder 6 being formed as shown in Fig. 10 and the projection 9 of the loop bar being angularly disposed to cooperate therewith. The wire 4 to supply the staple is fed between the projection 9 and the holder 6 in the plane of the latter, as clearly indicated in Figs. 3 and 5. As the staple is transferred by a direct lineal movement, it is presented in driving position at the end of the stapling arm at the same angle, and the driver is shaped to operate in the holder at such angle.

An advantage of this arrangement, among others, is that the box head may be stapled to the cleats at opposite sides with the staples approximately parallel and at such an angle to the sides of the cleats that the staple points or ends, when driven, are deflected toward and across the longitudinal centre line of the cleats instead of toward the sides thereof. Thus, as shown in Fig. 19, the legs of each staple become firmly em-

bedded in the body of the cleat instead of passing out at one or both sides thereof, thereby exerting a maximum holding power and the box head is firmly and uniformly held in place.

The mechanism described may be actuated from the driving shaft 21 by any suitable means, for example, by the instrumentalities shown in the drawings, which will now be described.

The staple driver 5 is operated by a medially fulcrumed lever 5^a having its forward end connected to the staple driver, by a pin and slot connection 5^b and having its rear end provided with a roller 5^c engaged by a cam 5^d on the shaft 21, said cam having a projection to operate the lever to give the staple driver a quick up stroke and allow its prompt return through the action of spring 5^e, as it is desirable to withdraw the driver from the staple holder before the latter is drawn backward.

The staple carrier 7, which should have a quick movement in each direction, and a sufficient period of rest in each extreme position for the staple forming and driving operations, respectively, is connected by a rod 7^a to a lever 7^b, the latter being operatively connected by a link 7^c with one arm of an angle lever 7^d, the other arm of which carries a roller 7^e for actuation by cam 7^f. This leverage arrangement is designed to give the desired length of stroke. Cam 7^f is of the segment type, and adapted, through the lever connections to impart a quick forward movement to the staple carrier, hold it in its forward position during a substantial time interval, allow its quick return, which is effected by a retractile spring 7^g, and to permit it to remain in its rearmost or staple-receiving position for an interval of approximately one-third the cycle of the cam shaft.

The loop bar 8, which as before stated, operates the wire cutter by its initial downward movement, is operated by a lever 8^a, the forward arm of which is connected to the loop-bar by a pin and slot connection 8^b, and the rear arm of which carries a roller 8^c arranged to be lifted at the proper period by a projection on cam 8^d to cause the down stroke of the loop bar, the up stroke being caused by a spring 8^e.

The staple wire feed mechanism is operated by a pawl 12^a and ratchet 12^b, the pawl being carried by a lever loosely journaled on the shaft of the feed wheel 12, and reciprocated by connecting rod 12^c from lever 12^d pivoted at 12^e and which carries at its upper end a roller 12^f engaged by cam 12^g on the shaft to operate the lever to feed the wire, the return motion of the lever being effected by a spring 12^h.

As will be understood, the cams are so timed and the arrangement of the parts is

such that in each cycle or revolution of the shaft, the loop bar 8 moves down to cut the wire and form the staple; the carrier 7 then quickly advances the staple to driving position, the driver moves up and drives the staple and withdraws, and the carrier quickly returns to position to receive another staple, the loop bar having meanwhile ascended and the wire for the next staple having been fed in.

Referring to Figs. 1, 15 and 16, a clamping and clinching device to cooperate with the staple driver, is carried at the end of the arm 3. This device, as shown, consists of a vertical plunger 30 operated by a lever 31 which at its forward end has a pin and slot connection with the plunger. Said lever is operated to force down the plunger by a cam lever 32 engaging a roller 33 carried by the lever 31 and the lever 31 is retracted by a spring 34. The cam lever 32 is connected by a rod 35 with an operating lever 36 having a roller engaged by a cam 37 on shaft 21. Concurrently with other action of the staple driver, the plunger is forced down to clamp the box head and to serve as an anvil or clincher to oppose the action of the staple driver and clinch the ends of staples which may be driven through the box materials. The timing should be such that the plunger 31 clamps the work before the staple is driven. The plunger rises and releases the work after the driving of each staple enabling the operator to move the box on the stapling arm the required distance for driving the next staple.

The requisite motion of the clincher to clamp the box will of course vary according to the thickness of the box head and cleat; for instance, a greater movement will be required to clamp a thin head than a thick one. In order that the clinching mechanism may automatically accommodate itself to the thickness of the work to be clamped, the connecting rod 35 is made in two parts, connected by a spring 38 which, after the work is clamped, permits continued action of lever 36 by the cam 37 with only a yielding pull on the end of the rod connected to the cam lever 32. The cam on the lever 32 is so formed and is in such relation to the roller 33 that the upward pressure of the roller is in the line of centers of the roller and cam so that there is always a substantially positive lock in whatever position the clincher or plunger 30 clamps the work. Thus, the need of manual adjusting means to accommodate the clinching mechanism to the work is obviated.

It will be noted that the nose of the arm 3 which carries the clamping and clinching mechanism, like the nose of the stapling arm 2, is so formed as to permit it to be inserted within the box and into the corners and close to the sides thereof. Thus either the clinch-

ing arm or the stapling arm or both may operate within the box, close to the sides thereof and in the corners.

Advantages of this arrangement, among others, are that the machine may be utilized to staple partitions or partitioning sections within the box and if desired may be operated to form and drive the staple outside the box and gauge and clinch the staple within the box.

The manner of using the machine will be clearly understood by those skilled in the art, and is indicated in Figs. 1 and 18 of the drawings, showing an ordinary wire-bound box with foldably connected side and bottom sections provided with cooperating end cleats and heads or ends arranged inside the cleats to be stapled thereto. In performing the stapling operation, the end board or box head rests upon the stapling arm, as shown Fig. 1, and the operator manipulates the box on said arm while operating the machine successively to drive a row of staples through each cleat; that is to say, through the head or end board along lines which cause the staples to pass into the cleats and in this operation, the tapered nose or terminal of the staple arm serves as a guide for enabling the operator to position the work and to gauge the staples from the box sides.

Power for operating the machine may be applied in any suitable manner, as for instance, by the power pulley 39 shown in Fig. 2 which may be controllably clutched to the shaft 21 by any suitable clutch mechanism.

Obviously the present invention is not limited to the specific embodiment illustrated and described, which may be variously modified in details of construction and arrangement, and features of the invention may be used in various machines embodying the invention, and in various combinations.

I claim as my invention and desire to secure by Letters Patent:

1. A machine for use in making boxes functioning to fasten heads, ends, partitions, or the like to boxes, which comprises, in combination, a staple driver; a staple carrier; and means to form a staple in said carrier; said driving, carrying and forming mechanisms being carried by an arm adapted to enter a box, and said mechanisms being constructed and arranged to operate within a box and to form the staple with its legs vertical and drive it vertically upward into the work.

2. A machine for use in making boxes functioning to fasten heads, ends, partitions, or the like to boxes, which comprises, in combination, staple-forming mechanism to form a staple in a staple-holder; a staple-driver adapted to drive the staple from the

holder in which it is formed; and means to present said holder to said driver; said staple-forming and driving mechanisms being carried by an arm adapted to enter a box, and said mechanisms being constructed and arranged to operate within a box and close to the sides thereof.

3. A machine for use in making boxes functioning to fasten heads, ends, partitions, or the like to boxes, which comprises, in combination, cooperating members to form a staple with its legs in a vertical plane, one of such members slidable to position the staple for driving, and a driver to drive said staple from said member vertically upward; said staple-forming and driving mechanisms being carried by an arm adapted to enter a box, and said mechanisms being constructed and arranged to operate within a box and close to the sides thereof.

4. A machine for use in making boxes functioning to fasten heads, ends, partitions, or the like to boxes, which comprises, in combination, cooperating members to form a staple, one of such members reciprocable to position the staple for driving, and a driver for driving the staple from said reciprocable member in the opposite direction from which it is formed; said staple-forming and driving mechanisms being carried by an arm adapted to enter a box, and said mechanisms being constructed and arranged to operate within a box and close to the sides thereof.

5. A machine for use in making boxes functioning to fasten heads, ends, partitions, or the like to boxes, which comprises, in combination, oppositely acting staple forming and driving instrumentalities, and cooperating means movable therebetween to receive, hold and transfer the staple; said staple-forming and driving mechanisms being carried by an arm adapted to enter a box, and said mechanisms being constructed and arranged to operate within a box and close to the sides thereof.

6. A stapling machine comprising, in combination, oppositely acting staple forming and driving instrumentalities, and cooperating means movable therebetween and along an inclination to the lines of action of said instrumentalities to receive, hold and transfer the staple.

7. An end stapling machine for forming and driving staples within a box, comprising in combination, staple forming mechanism including, a holder and a movable loop bar to form a staple in said holder; a driver adapted to drive a staple from the holder when the latter is in alignment therewith; and means to shift the holder from staple forming position to staple driving position; said staple-forming and driving mechanisms being carried by an arm adapted to

- enter a box, and said mechanisms being constructed and arranged to operate within a box and close to the sides thereof.
8. A machine for securing box heads by inserting staples from within the box, to fasten the heads to cleats on the box sides, comprising an arm and a staple-forming and driving mechanism carried thereby arranged for operation within the box to 10 form a staple and drive it from the terminal of said arm, including devices for forming the staple with its legs vertical to the horizontal line of said arm and for positioning it for driving from said terminal 15 by a forward shift without tilting the staple, said terminal adapted to reach into the box corners and to be engaged successively by the box sides to gauge the position of the staple.
9. An inside box stapling machine comprising an arm and a staple forming and driving mechanism carried thereby arranged for operation within the box to form a staple and drive it from the terminal of 20 said arm, including means to position the staple for driving from said terminal in a plane at an angle to the longitudinal and transverse axes of said arm, said terminal adapted to reach into the box corners and 25 to be engaged successively by the box sides to gauge the position of the staple.
10. A machine for securing box heads by inserting staples from within the box, to fasten the heads to cleats on the box 30 sides, comprising an arm and a staple forming and driving mechanism carried thereby arranged for operation within the box, provided with devices for forming the staple in a plane at an angle to the longitudinal 35 and transverse axes of said arm and shifting the staple and driving it from the terminal of said arm while maintaining it in substantially the relation to said axes in which it was formed, said terminal 40 adapted to reach into the box corners and to be engaged successively by the sides of the box to gauge the position of the staple.
11. A machine for securing box heads by inserting staples from within the box, to 45 fasten the heads to cleats on the box sides, comprising an arm and a stapling mechanism carried thereby arranged for operation within the box, provided with devices for supplying a staple in position for driving from the terminal of said arm with the staple positioned in a plane at an angle to the longitudinal and transverse axes of said 50 arm and with means for driving it in said position, said terminal adapted to reach 55 into the box corners and to be engaged successively by the box sides to gauge the position of the staple.
12. An inside box stapling machine comprising an arm and a staple-forming and 60 driving mechanism carried thereby arranged 65 for operation within the box to form a staple with its legs vertical to the horizontal line of said arm and to drive it from the terminal of said arm, including a movable staple-holder in which the staple is formed 70 and from which it is driven into the work, said terminal of the arm adapted to reach into the box corners and to be engaged successively by the sides of the box to gauge 75 the position of the staple.
13. An inside box stapling machine comprising an arm and a staple forming and driving mechanism carried thereby arranged for operation within the box to form a staple and drive it from the terminal of 80 said arm; said mechanism comprising a sliding staple holder to receive a staple and position it at said terminal for driving; staple-forming means cooperating therewith in one position to form a staple in 85 said holder, and a driver positioned at the terminal of said arm and operating transversely of the line of movement of said holder to drive the staple from said holder.
14. A stapling machine comprising, in combination, a staple driver, and wire guiding, cutting, staple forming and transfer devices associated with said staple driver, said transfer device adapted to receive the staple and movable along an inclined path 90 to a position for holding the staple for driving, said driver and said other devices operating on opposite sides of said path.
15. A stapling machine comprising, in combination, oppositely acting staple forming and driving instrumentalities; means movable along an inclined path in the plane of said instrumentalities to receive the staple and transfer it to position for driving; and staple wire feeding, guiding and 95 cutting devices arranged to present the wire to form a staple across and at an inclination to said plane; the staple forming and transfer means constructed and arranged to form the staple in the angular plane in 100 which the wire is presented and to hold it at the same angle during transfer and while 105 in position for driving.
16. A stapling machine having a lineally movable staple holder, cooperating wire presenting and staple forming means, said holder and means cooperating in one position of the holder to form therein a staple positioned in a plane at an angle to the line of movement of the holder, and means 110 adapted to enter the holder in another position for driving the staple.
17. A stapling machine comprising, in combination, a reciprocable staple carrier having a holder for receiving a staple, cooperating means to form a staple in said holder, a driver to enter the opposite end of the holder to drive out the staple, said carrier in one position aligning said holder 115 with said cooperating staple forming means 120
- 18

- and in another position alining it with said driver, said staple-forming and driving mechanisms being carried by an arm adapted to enter a box, and said mechanisms being constructed and arranged to operate within a box and close to the sides thereof. 55
18. A machine of the class described having a staple forming and driving mechanism arranged for operation within a box,— 60
- 19 which comprises, in combination, a support for said mechanism arranged to enter and engage the sides of the box to gauge their positions; a staple driver at the end of said support; means to feed staple wire across said support at an angle to the longitudinal axes of the machine; means to cut the wire; means to form a staple in a vertical plane at the same angle as the wire; and means to transfer the staple, while keeping it at the same angle, to position for driving from the end of said support. 70
20. A stapling machine comprising, in combination, staple forming and driving mechanism, and associated means to supply wire for a staple, including a movable guide tube having a wire-shearing end and a shearing member co-acting therewith; said staple-forming and driving mechanisms being carried by an arm adapted to enter a box, and said mechanisms being constructed and arranged to operate within a box and close to the sides thereof. 75
21. A machine for use in making boxes functioning to fasten heads, ends, partitions, or the like to boxes, which comprises, in combination, a staple driver; a movable clincher cooperating therewith; and clincher operating means including a yielding means to enable the clincher to adapt itself to different thicknesses of work and offer a positive resistance to the driver. 80
22. A machine for use in making boxes functioning to fasten heads, ends, partitions, or the like to boxes, which comprises, in combination, a staple driver; a movable clincher cooperating therewith and adapted to offer positive resistance to said driver; means for operating the clincher; and means rendering the clincher self-adjustable to different thicknesses of work. 85
23. A machine for use in stapling box heads or partitions comprising a pair of arms one carrying staple forming and driving mechanism and the other carrying clincher mechanism, said arms being so constructed and arranged that either or both may enter the box, close to the sides thereof and in the corners to gauge and position the staples. 90
24. An inside box stapling machine for use in stapling box heads to box cleats comprising, an arm carrying cooperating mechanism for cutting and forming a staple with oppositely disposed points in a vertical plane at an angle to the longitudinal and transverse axes of said arm, and means for driving said staple in said plane and at said angle into a cleat, said arm being adapted to reach into box corners and to be engaged by box sides to gauge the position of the staple, whereby the staple may be driven into the cleat in a plane at an angle to the longitudinal and transverse axes of the cleat and the legs of the staple will be deflected in opposite directions toward the medial longitudinal axis of the cleat. 95
25. A machine for use in making boxes functioning to fasten heads, ends, partitions, or the like to boxes, which comprises, in combination, staple forming mechanism, including a holder adapted to remain stationary during a forming operation and a movable loop bar cooperating therewith; and a driver adapted to drive a staple from said holder into the work; said staple-forming and driving mechanisms being carried by an arm adapted to enter a box, and said mechanisms being constructed and arranged to operate within a box and close to the sides thereof. 100

In testimony whereof, I have signed my name to this specification.

OSCEOLA C THOMPSON.
